EYE SHIELD

Ted Zbikowski, Detroit, Mich., assignor to Joseph Buegeleisen Co., Oakland, Mich.

Filed Feb. 9, 1962, Ser. No. 68,756

Term of patent 14 years

(Cl. D57—1)

FIG. 1

FIG. 2

FIG. 1 is a front elevational view of an eye shield, showing my new design.

FIG. 2 is a side elevational view thereof.

FIG. 3 is a top plan view thereof.

The side not shown is substantially the same as the side shown.

This application is a continuation-in-part of my earlier filed application, Serial No. 63,551, filed January 13, 1961, now abandoned.

I claim:

The ornamental design for an eye shield, as shown and described.
